(57) **CLAIM**

The ornamental design for a wrench socket, as shown and described.

DESCRIPTION

FIG. 1 is a front perspective view of a socket according to the present invention;

FIG. 2 is a rear perspective view thereof;

FIG. 3 is a front elevational view thereof;

FIG. 4 is a rear elevational view thereof;

FIG. 5 is a right side view thereof, the left side view being a mirror image of the right side view and therefore not illustrated;

FIG. 6 is a top plan view thereof; and,

FIG. 7 is a bottom plan view thereof.
